DISPENSING APPLICATOR FOR CLEANING UPHOLSTERY

Howard A. Anderson, Pittsburgh, Pa., assignor to Bissell
Inc., Grand Rapids, Mich., a corporation of Michigan

Filed Feb. 15, 1963, Ser. No. 73,582

Term of patent 14 years

(Cl. D9—2)

Fig. 1

Fig. 2

Fig. 3

The container is shown broken away in FIGURE 2 for convenience of illustration.

The broken lines shown in FIGURES 1, 2, 3 and 4 are for illustrative purposes only.

I claim:

The ornamental design for a dispensing applicator for cleaning upholstery, substantially as shown and described.
